(57) **CLAIM**

The ornamental design for an aiming element for toy gun kit, as shown and described.

DESCRIPTION

FIG. 1 is a front view of the aiming element for toy gun kit showing my new design;
FIG. 2 is a back view thereof;
FIG. 3 is a left view thereof;
FIG. 4 is a right view thereof;
FIG. 5 is a top view thereof;
FIG. 6 is a bottom view thereof;
FIG. 7 is a perspective view thereof;
FIG. 8 is a front view in a flip-up position thereof;
FIG. 9 is a back view in a flip-up position thereof;
FIG. 10 is a left view in a flip-up position thereof;
FIG. 11 is a right view in a flip-up position thereof;
FIG. 12 is a top view in a flip-up position thereof;
FIG. 13 is a bottom view in a flip-up position thereof; and,
FIG. 14 is a perspective view in a flip-up position thereof.
The broken lines represent portions of the article that form no part of the claim.
